UNITED STATES PATENT OFFICE.

EDWARD M. COLLES, ROBERT C. KITCHELL, AND DAVID C. APPLEGATE, OF PRINCETON, INDIANA.

WASHING-MACHINE.

SPECIFICATION forming part of Letters Patent No. 427,745, dated May 13, 1890.

Application filed September 13, 1889. Serial No. 323,810. (No model.)

To all whom it may concern:

Be it known that we, EDWARD M. COLLES, ROBERT C. KITCHELL, and DAVID C. APPLEGATE, citizens of the United States, residing 5 at Princeton, in the county of Gibson and State of Indiana, have invented a new and useful Washing-Machine, of which the following is a specification.

Our invention relates to improvements in 10 washing-machines; and it consists in certain novel features hereinafter described and claimed.

In the accompanying drawings, Figure 1 is a perspective view of our improved washing- 15 machine. Fig. 2 is a vertical section of the same. Fig. 3 is a detail view of the wash-board. Fig. 4 is a detail sectional view of the same.

Referring to the drawings by letter, A des- 20 ignates the tub, which may be of any desired size and shape and is supported by the legs B, as shown.

On two of its sides the tub is provided with 25 the bars C, which serve as handles by which the device can be conveniently carried from one point to another.

The tub is provided with a swinging lid D in its top, and the said lid is provided with a central opening E and a circular boss F on 30 its outer side surrounding said opening. The agitator-shaft G is mounted in this opening, and is provided with an annular shoulder H, which bears on the upper side of the boss F, so as to prevent the shaft being pushed too 35 far into the tub. The shaft is provided at its upper end with a lever or handle I, having the knobs J at its ends, which can be conveniently grasped by the operator to vibrate the said lever. At the lower end of the agitator- 40 shaft is secured the block or agitator-head K, which bears against the under side of the lid, so as to prevent the withdrawal of the said shaft, and to the said block we secure the depending radiating-pins L, which are adapted 45 to act on the clothes, so as to agitate the same in the water and throw them against the wash-board.

The wash-board is composed of a series of cylindrical rubbing-bars M, which are flexibly connected by short links N, which may be of 50 any desired construction, and the elastic sleeves or washers O, surrounding the said links. The wash-board is fitted around the sides of the tub with the rubbing-bars in a vertical position, so that as the clothes are 55 agitated and thrown toward the sides of the tub they will be carried back and forth over the rubbing-bars and the dirt thoroughly removed therefrom.

The clothes are placed in the tub together 60 with soap and water and, if so desired, a suitable cleansing compound, and the lever I on the upper end of the agitator-shaft is vibrated, so as to impart motion to the agitator and thereby throw the clothes against the 65 wash-board so as to cleanse the same.

It will be observed that our device is very simple in its construction, so that it is not liable to get out of order, and that it can be easily operated by any person. The con- 70 struction of the wash-board is such that it can be readily removed and rolled or folded into a compact bundle, so that it may be easily transported, and may be fitted to tubs of various sizes and shapes. 75

Having thus described our invention, what we claim, and desire to secure by Letters Patent, is—

The wash-board for washing-machines, con- 80 sisting of cylindrical rubbing-bars flexibly connected by links and the elastic washers arranged around the links between the rubbing-bars, as set forth.

In testimony that we claim the foregoing as our own we have hereto affixed our signatures 85 in presence of two witnesses.

EDWARD M. COLLES.
ROBERT C. KITCHELL.
DAVID C. APPLEGATE.

Witnesses:

LEVIN W. GUDGEL,
CHARLES F. APPLEGATE.
